UNITED STATES PATENT OFFICE.

RUDOLPH PETERSON, OF DE KALB, ILLINOIS, ASSIGNOR TO KOHLER DIE & SPECIALTY COMPANY, OF DE KALB, ILLINOIS, A CORPORATION OF ILLINOIS.

ROLLER SKATE.

Application filed March 10, 1921. Serial No. 451,236.

To all whom it may concern:

Be it known that I, RUDOLPH PETERSON, a citizen of the United States, residing at De Kalb, in the county of De Kalb and 5 State of Illinois, have invented certain new and useful Improvements in Roller Skates, of which the following is a specification.

This invention relates to roller skates but more particularly to the extensible type, and 10 has for its primary object to produce a simplified and improved construction providing increased strength, rigidity and durability.

The present invention is particularly an improvement on the skate construction shown 15 and described in United States patents granted to Thomas Spacie Nos. 917,499 and 1,208,681 of April 6, 1909 and December 12, 1916 respectively, and reference may be had thereto for a more complete description of 20 the general skate construction.

The further objects and advantages of my invention will be better understood by reference to the following specification when considered in connection with the accompanying drawing illustrating a selected embodiment thereof, in which:—

Fig. 1 is a side elevation of a roller skate embodying my invention complete.

Fig. 2 is a bottom plan view of the forward skate member.

Figs. 3 and 4 are sections respectively on the lines 3—3 and 4—4 of Fig. 1, and

Fig. 5 is a perspective view of the rear brace of the forward skate member.

Referring to the drawing, the skate comprises a sole plate 5 and a heel plate 6 connected by the extension bar 7. This bar has its rear end permanently secured to the heel plate 6 and the front end thereof is 40 adapted to be adjustably secured to the sole plate 5 to permit variation in the length of the skate.

The forward rollers 8 are mounted upon an axle 9 supported by a cradle 10. A 45 cushion 11 of resilient material is held between the front and rear parallel lugs 12 having aligned apertures to receive the pivot pin 13. A cap 14 fits over the cushion 11 and is provided with slots 15 and 16 through 50 which project the lower extremities of the front and rear braces 17 and 18 respectively. The pivot pin 13 passes through perforations in these braces.

The rear brace 18 is secured to the sole 55 plate 5 by rivets 21 or other suitable means.

The upper portion of this brace extends rearwardly beneath the plate and a channel 22 is formed in its upper face in alignment with an opening 23 in the front brace 17 to admit the forward portion of 60 the bar 7. This bar is slidable longitudinally in the channel to permit adjustment of the length of the skate for the various shoe sizes. The rear portion of the channel is depressed at 24 to receive a nut 25. 65 A binding screw 26 projects through the brace and nut and is adapted to engage the under face of the bar 7 to permit this bar to be locked in its adjusted position.

In skates of this type it has heretofore 70 been customary to use an anchor plate separate from the rear brace to receive and support the forward portion of the bar. The rear portion of this plate was secured to the under face of the sole plate by rivets and 75 the forward end projected into the opening in the upper end of the rear brace which admitted the bar. This construction proved a serious source of weakness in the skate on account of the severe strain upon these parts 80 produced by the leverage of the bar, particularly when the skate was extended sufficiently to withdraw the bar from the opening in the rear brace. Furthermore, this form of anchor plate failed to produce the 85 necessary rigidity in the connection between the front and rear skate members. By extending the rear brace and forming the the channel for the bar in this brace, the portion of the brace connecting the sole 90 plate and the pivot pin is strengthened and its rigidity very materially increased. In the same manner the portion of the brace performing the function of the anchor plate 95 provides a far stronger and more rigid support for the extension bar, as will be readily evident.

In addition to the increase in strength and rigidity provided by the extended rear brace, the cost of production of the skate is materially reduced. This brace may be readily formed from sheet metal by a single operation of the press. All rivets for connecting this brace to the sole plate may be applied in a single operation. The horizontal extension of the rear brace forms a trust construction supporting the sole plate which materially strengthens this plate. Likewise the connection of the rear brace to the sole plate at widely spaced points rigidly posi- 105 110

tions this brace and thus strengthens the entire support for the front axle.

I am aware that changes may be made in the construction and arrangement of the 5 parts without departing from the spirit of my invention and I reserve the right to make all such as fairly fall within the scope of the following claims.

I claim:

- 10 1. In a roller skate, a sole plate, a heel plate, an extension bar rigidly secured to said heel plate and projecting forwardly therefrom to form a connection between said plates, a front axle, and supporting means 15 for said axle including front and rear braces, said rear brace being provided with a rearwardly projecting substantially channel shaped extension forming with said sole plate a socket to receive the forwardly projecting portion of said bar.
- 20 2. In a roller skate, a sole plate, a heel plate, an extension bar rigidly secured to said heel plate and projecting forwardly therefrom, to form a connection between said plates, a front axle, and supporting means for said axle including front and rear braces, said rear brace being provided with an integral channel-shaped extension projecting rearwardly

beneath said sole plate and having its rear 30 end secured thereto to form a socket to receive the forward portion of said bar.

3. In a roller skate, a sole plate, a heel plate, an extension bar connecting said plates a front axle, and supporting means for said 35 axle including front and rear braces, said rear brace comprising a substantially vertical portion secured at its upper end to said sole plate and connected at its lower end to said axle, and a substantially horizontal portion projecting rearwardly from said vertical portion and having its rear end secured to said sole plate at an interval from the point of fastening of said vertical portion.

4. In a roller skate, a sole plate, a heel 40 plate, an extension bar secured to said heel plate and projecting forwardly therefrom to form a connection between said plates, a front axle, and supporting means for said 45 axle including front and rear braces, said rear brace being connected substantially at its upper end to said sole plate and having a substantially channel shaped extension projecting rearwardly beneath the sole plate from said connection to form with said sole 50 plate a socket to receive the forwardly projecting portion of said bar.

RUDOLPH PETERSON.
